[57] CLAIM

The ornamental design for a combined bottle and cap, as shown and described.

DESCRIPTION

FIG. 1 is a front elevation of a combined bottle and cap showing my new design;

FIG. 2 is a rear elevation thereof;

FIG. 3 is a perspective view thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a front elevation of an alternate embodiment of the combined bottle and cap;

FIG. 9 is a rear elevation of FIG. 8;

FIG. 10 is a perspective view of FIG. 8;

FIG. 11 is a right side elevation of FIG. 8;

FIG. 12 is a left side elevation of FIG. 8;

FIG. 13 is a top plan view of FIG. 8; and

FIG. 14 is a bottom plan view of FIG. 8.
